THEODORE BARKER, OF MEXICO, NEW YORK, ASSIGNOR TO JAPHET LIN-
GENFELTER, OF SAME PLACE.

Letters Patent No. 80,850, dated August 11, 1868.

IMPROVED BRICK-MACHINE.

The Schedule referred to in these Letters Patent and making part of the same.

TO ALL WHOM IT MAY CONCERN:

Be it known that I, THEODORE BARKER, of Mexico, in the county of Oswego, and State of New York, have invented certain new and useful Improvements on Brick-Making Machinery; and I do hereby declare that the following is a full, clear, and exact description thereof, reference being had to the accompanying drawings, making a part of this specification, in which—

Figure 1, sheet 1, is a front elevation of the improved machine.

Figure 2, sheet 1, is an elevation of one side of the machine.

Figure 3, sheet 2, is a section taken through the machine, below the pug-mill and press-box, in the horizontal plane indicated by red line $y\ y$ in fig. 1.

Figure 4, sheet 2, is a longitudinal section taken through the machine, in the vertical plane indicated by red line $x\ x$ in fig. 1.

Similar letters of reference indicate corresponding parts in the several figures.

This invention relates to certain novel improvements on that class of brick-making machinery wherein the clay is pulverized and mixed in a vertical pug-mill, and discharged laterally therefrom into a press-box, which is applied to one side of this mill, from which box the clay is forced directly into mould-boxes, which are moved beneath it.

The nature of my invention and improvement consists in the employment, in this class of machine, of a driving-belt, for transmitting motion from the main driving-shaft of the pug-mill to the followers, which move the mould-boxes beneath the press-box, for the purpose of guarding against derangement and breakage of the machine, should it become clogged by foreign substances in the clay, said belt being provided with a device by which it can be made to hug upon its drums with more or less force, according to the power required to be transmitted through it, as will be hereinafter described.

The invention also consists in providing for feeding the empty mould-boxes from a receiving-table, arranged on one side of and beneath the plane of the pug-mill, to a point which is beneath the press-box, and then moving the mould-boxes, when filled, upon a delivery-table in front of the press-box, by means of certain levers and connecting-rods, which are arranged beneath the plane of said tables, and which receive motion from the pug-mill shaft, as will be hereinafter described.

The invention further consists in communicating an intermittent vertical reciprocating motion to the plunger, which forces the clay from the press-box into the mould-boxes by means of a reciprocating cross-head and an adjustable bearing, said cross-head being applied upon guide-rods extending up from the plunger, and allowed to slide independently of said rods and plunger, in the act of rising while the press-box is being filled, and also in the act of descending to commence the operation of pressing, as will be hereinafter described.

The invention further consists in providing a vertical pug-mill, having a press-box upon its side, with a clay-elevator, which is so constructed and applied that it will elevate and discharge the clay into the pug-mill, at the top thereof, without requiring manual labor to perform this work, as will be hereinafter described.

To enable others skilled in the art to understand my invention, I will describe its construction and operation.

In the accompanying drawings, A represents an upright frame, which is adapted for containing and supporting the mechanism for mixing the clay, forcing it into the mould-boxes, and moving these boxes beneath the press-box. Within this frame is constructed the pug-mill box B, which is open at its top, and closed at its bottom, except at a, where there is a lateral opening for the discharge of the clay into the press-box B¹.

In the centre of the pug-mill box B is a vertical shaft, C, which is stepped upon the bottom of this box, and passed through a horizontal head-block, A¹, carrying upon its upper end a large bevel-spur wheel, C', and a lever or sweep, to which the animals are hitched that operate the machine. This vertical shaft C should be provided with radial arms or blades, for stirring, pulverizing, and mixing the clay, preparatory to discharging it into the press-box B¹, and, at the lower end of this shaft, blades should be applied, which will force the clay

into the press-box. The press-box B^1 is of a rectangular shape, and is secured rigidly to the front side of the pug-mill box, so as to receive the clay from this box beneath a vertically-reciprocating plunger, B^2 . The front side of the box B^1 is provided with a hinged door, a' , for affording access to it beneath the plunger, and the bottom of this box is constructed in the well-known manner, with a grating, s , consisting of parallel bars, between which the clay is forced and divided, in its passage into the cells of the mould-boxes. The plunger B^2 is constructed with a plate extending up from its back edge, which forms a cut-off, for preventing clay from being forced over the pressing-plate of the plunger when this plate descends below the top of the opening a , as shown in fig. 4. In the middle of the width of the plunger B^2 , and arranged at equal distances from the ends thereof, two vertical rods, e , are secured rigidly to it, which rods extend up through bracket-guides e^1 e^1 on the press-box, and also through bracket-guides e^2 e^2 , which are secured to the pug-mill box B^1 , as shown in fig. 1. By means of these guides, the rods e will keep the plunger B^2 always in a plane parallel to the bottom of the press-box, and allow the plunger to be raised and depressed. The guide-rods e also pass through the tubular extremities of a cross-head, f , which is interposed between lifting-pins f' f' , on the guide-rods, and an adjustable screw, g , upon the plunger. This cross-head is allowed to slide up and down between said parts independently of the guide-rods and plunger, so that the plunger shall remain stationary during a portion of the ascending and descending strokes of the cross-head f . The screw g is tapped into a tubular socket, g^1 , which rises some distance above the top of the press-plate of the plunger, and this screw is used so that, by adjusting it, the plunger can be depressed more or less, according to the density it is required to make the bricks.

The cross-head f receives motion from a crank, g^2 , through the medium of a connecting-rod, D , which crank is keyed upon the front end of a horizontal shaft, D^1 , that has its bearings upon top of frame A , and that receives its rotation from the large horizontal bevel-wheel C , by means of the pinion-spur wheel D^2 .

Beneath the press-box and pug-mill, and extending out in front of the press-box, as shown in figs. 2 and 4, is a table, E , which is constructed with rollers, h h , upon that portion of it which is beneath the press-box, and which is hinged at its rear end to vertically-adjustable bearings, t t , in any suitable manner. The forward portion of the table E is supported upon toes, i i , which are secured to a horizontal rock-shaft, E^1 , which shaft is supported by vertically-adjustable stirrups, j j , upon the two front uprights of the frame A . An arm, E^2 , projects at right angles from one end of the shaft E^1 , which is used for rocking this shaft when it is desired to depress or elevate the front end of the table. When the table is in a horizontal plane, parallel to the bottom of the press-box, the arm E^2 will be held in an upright position, by the catch k , upon one of the standards of the frame A , as shown in figs. 1 and 2. The table E can be adjusted up or down bodily, by loosening the four bearings, t t , j j , upon which it is supported.

On one side of the table E , and at right angles thereto, is a receiving-table, F , which is supported in the same horizontal plane as the table E , by means of legs F' at its outer end, and pins or studs at its inner end, which latter enter holes made in one of the side bars of the table E , and allow the receiving-table F to be removed at pleasure. This receiving-table F has a central slot through it, extending its entire length, which slot serves as a guide for a sliding follower, S , that is intended for moving the empty mould-boxes endwise upon the table E , in rear of the press-box, and leaving them in a position, upon this table E , to be moved beneath the press-box by means of a follower, G . The follower G is hung from parallel slotted ways, l l , secured to the bottom of the pug-mill box B , and moved back and forth by means of a connecting-rod, G^1 , and crank-arm, G^2 .

The crank-arm G^2 is keyed upon a horizontal shaft, G^3 , which is supported by frame A beneath the pug-mill box, as shown in fig. 3, and on the outer end of the shaft G^3 a belt-drum, H , is keyed.

The follower G receives a regular rectilinear reciprocating movement, and when it has moved a mould-box beneath the press-box, it recedes, to allow of the introduction of another empty box behind the one being filled, during the filling operation, after which this follower G pushes the filled box from beneath the press-box to the front part of the table, and at the same time pushes the said empty box beneath the press-box.

The followers G and S operate alternately upon the mould-boxes; that is to say, while the follower G is receding from the press-box, after having moved an empty box under it, the follower S is advancing, and moving an empty box upon the table E . The follower S is connected by a rod, I , and swivel-joints, to the longest arm of a horizontally-vibrating lever, J , the shortest arm of which is connected by a rod, J' , and swivel-joint, to the rod G^1 , which connects the follower G to its crank-arm G^2 . The vibrating lever J is pivoted to a fixed stud, m , which projects perpendicularly from the wide sill A^3 of frame A , and the long arm of this lever is supported in its vibrating movements by a small wheel, m' , which rolls upon said sill, as shown in fig. 1. The short bent arm of the lever J has a wrist-pin, n , projecting up from it, which passes through an oblong slot that is made through the front part of the rod J' , as shown in fig. 3. By means of this slotted rod J' , the connecting-rod G^1 is caused to communicate an intermittent motion to the follower S , so that this follower is allowed to remain stationary for a short time at the terminus of each one of its strokes. This will allow time for adjusting an unfilled or empty mould-box upon the table F , in front of the follower S , and it will also allow the follower G to recede out of the way before the follower S moves an empty box upon the table E .

The shaft G^3 receives motion from the pug-mill shaft C , through the medium of the belt K , belt-wheels H H^1 , shaft K^1 , and spur-wheels K^2 and C^1 . The shaft K^1 has its bearing on top of the frame A , and is at right angles to the shaft D^1 , which operates the plunger B^2 . The belt K is provided with a device which will allow of its being tightened at pleasure, which device consists of an anti-friction roller, o , applied to the end of a sliding frame, p , which frame is guided by a bracket, L , upon one side of the frame A . By means of the screw p' , the frame p can be adjusted forward or backward, and any degree of tightness given to the belt which may be found necessary in working the machine.

At the rear side of the frame A , I apply an elevator for raising the clay from a point near the base of the machine, and discharging this clay into the upper end of the pug-mill. This elevator consists of a trunk, D ,

suitably inclined and supported, and provided with an endless-screw flange, b^1 , upon a rotary shaft, D^3 . This trunk has a funnel or receiving-box, D^2 , near its lower end, into which the clay to be raised is put, and in this box is a number of radial wings, b , upon a shaft, b^2 , which receives rotation from shaft D^3 , through the spur-wheels c c' , shown in fig. 4. The shaft D^3 carries a bevel-spur wheel, d , upon its upper end, which engages with a corresponding wheel, d^1 , upon the outer end of a horizontal shaft, D^4 , which has its bearing upon the top of the frame A. The shaft D^4 also carries a bevel-spur wheel, d^2 , which engages with the large horizontal spur-wheel C', on the pug-mill shaft C. When clay is thrown into the receiving-hopper D^2 , the blades b will force it rapidly into the lower end of the trunk D, where it will be acted upon by the screw-flange b^1 , elevated, and discharged into the pug-mill through the spout D ^{1} , thereby dispensing with manual labor for lifting the clay to the height of the pug-mill.

The operation of the machine is as follows: Motion is imparted to the pug-mill shaft C by animals, which are hitched to a long sweep projecting from the upper end of this shaft, and which are made to walk in a circle around the machine. The clay is elevated and discharged into the pug-mill, as above described, where it is mixed and thoroughly pulverized, and upon reaching the bottom of the said mill, it is discharged into the press-box B ^{1} beneath the plunger B ^{2} . At the proper time for commencing the operation of making bricks, a mould-box, consisting of a right-angular box, with as many cells in it as there are spaces between the bars s, forming the bottom of the press-box, is introduced upon the side table F, in front of the follower S, between raised guides v v, which are formed upon this table, as shown in fig. 3. This empty box will be moved laterally upon the table E, and left there. The follower G will then move forward and push this box beneath the press-box, where it will have its cells filled with clay by the descent of the plunger B ^{2} . While the plunger B ^{2} is operating, the follower G will recede and allow the follower S to move another empty mould-box behind the box which now contains the clay. The follower G will then advance and force the filled box from beneath the press-box, and at the same time force the next box in the place occupied by this filled box.

During the operation of discharging a filled mould-box from beneath the press-box, and introducing an empty box in its stead, the plunger B ^{2} will remain stationary at the highest point of its press-box, so that there will be no clay forced from the latter during this operation, and during the filling of a mould-box the follower G will bring another empty mould-box in position to take the place of said box when the plunger rises after completing its work. It will be seen that after the plunger B ^{2} is elevated to its highest point by the cross-head f, acting upon the lifting-pins f' f', upon guide-rods e e, this plunger remains stationary until the cross-head f descends, and impinges upon the head of the adjusting-screw g. This allows time for the filled mould to be pushed out upon the front end of the delivery-table E. It will also be seen that after the plunger has been depressed, it is allowed to rest until the cross-head f rises against the lifting-pins f'. This allows time for the follower S to move an empty mould-cell in front of the follower G, and in line with the press-box.

The tubular socket g ^{1} , in which the adjusting-screw g is tapped, is made long enough to afford a substantial support for this screw, and prevent clay from clogging it.

In this kind of brick-machine, it is very important to provide a safe remedy against derangement or breakage, should a stone or other hard substance in the clay get into the press-box. This has been attempted, before my invention, by a hinged section applied to the press-box, and connected by a tripping-device with the mould-table beneath the press-box, but such a contrivance is impracticable, on account of the uncertainty attending its operation at the proper time to save the machine from injury. The belt K and its tightening-device are found to effectually remedy the difficulty and danger, as this belt can be adjusted so that it will with certainty slip upon its drums when there is undue resistance beneath the press-box, and thus prevent the operation of the follower upon the mould-boxes. The danger of breaking the machine would occur if the mould-boxes were held fast by a hard substance becoming lodged between them and the press-box bottom, and when thus held, the follower is pressed upon them.

It will be seen that I drive my pug-mill press and elevator by means of toothed or spur-gearing, and that I drive the followers, which bring the moulds in proper position, by means of a belt and pulleys. Thus I obtain a positive and "ungiving" power for operating the pug-mill shaft, the pressing-follower and the elevator, and a yielding or relaxing power for operating the followers which bring up the moulds. Now, in the event that the empty moulds or anything belonging to the devices, intermediate between the followers and the belt K, should become cramped, or in the event of a mould-box which is being filled becoming bound or wedged by gravel or stones between the bottom of the press-box and the table E, and its discharge therefrom should require a great strain to come upon the devices which operate the mould-box-moving followers, and such strain should be so great as to endanger said devices, then the belt K slips and saves the devices from being broken. But this slipping of the belt does not stop the operation of the pug-mill, press-follower, and elevator, and therefore I have left a square extension, G ^{4} , on the shaft G ^{3} , and on this extension an attendant instantly fits a hand-lever, and by manual force, (the obstruction having been previously removed,) turns the pulley and shaft far enough to bring the mould-box-moving followers to a proper position for operating in concert with the press-follower. It will be understood that the spur-gearing is constructed strong enough to overcome all binding obstructions, and hence the hand-movement of the shaft G ^{3} may only be necessary to bring the parts in proper relation to one another, in order to have all operate harmoniously. The slip of belt may only be momentary, and its only design is to let the whole undue strain come upon that part of the machine which is constructed to bear it.

I am aware that it is not new to employ a side-receiving table for the mould-boxes, arranged at right angles to a delivery-table beneath the mill and press-box, with two followers operating in conjunction with these tables, and therefore I do not lay claim now to such arrangement in its broadest sense.

I am also aware that it is not new broadly to employ an intermittent reciprocating plunger, working in a

press-box which is arranged upon one side of a pug-mill, nor to combine with such feature a device by which bricks of different density can be made, by forcing more or less clay into the cells in mould-boxes, and therefore I do not lay claim broadly to any of these old devices.

Having described my invention, what I do claim as new, and desire to secure by Letters Patent, is—

1. Combining with the two tables F and E, arranged at right angles to each other, and the two followers S and G, the connecting-rod I, vibrating-lever J, and slotted rod J', arranged and operating substantially in the manner and for the purposes specified.

2. The arrangement of the slotted side-table F, ledges v v, follower s, suspending guide-ways l, and the suspended follower G, in a brick-machine, substantially in the manner shown and described.

3. The combination and arrangement of the guide-rods e e, applied to the plunger B², and provided with stops f' f', the cross-head f, its connections with the driving-shaft, the adjusting-screw g, and tubular socket or sleeve g¹, all substantially in the manner and for the purpose described.

4. The belt K, with its necessary adjuncts between the spur-gearred driving-power of the pug-mill and press, and the mechanism, constructed and arranged substantially as described, for bringing the mould-boxes into proper position, in the manner and for the purpose substantially as set forth.

5. The combination and arrangement of the devices set forth for automatically feeding, elevating, and discharging clay into the pug-mill, in the manner substantially as and for the purposes described.

THEODORE BARKER.
